N. FELLABAUM

PIPE TONGS

Filed Nov. 6, 1922

UNITED STATES PATENT OFFICE.

NEWTON FELLABAUM, OF SPERRY, OKLAHOMA.

PIPE TONGS.

Application filed November 6, 1922. Serial No. 599,338.

To all whom it may concern:

Be it known that I, NEWTON FELLABAUM, a citizen of the United States, residing at Sperry, in the county of Tulsa and State of Oklahoma, have invented certain new and useful Improvements in Pipe Tongs; and I do declare the following to be a full, clear, and exact description of the invention, such as will enable others skilled in the art to 10 which it appertains to make and use the same.

My invention relates to improvements in pipe tongs and more particularly to those of the type having a body carrying a fixed jaw, a movable jaw carried by the body, and a movable handle connected with said body for holding the movable jaw in tight contact with the work while the tongs are being operated.

20 The object of the invention is to provide an extremely simple and inexpensive, yet a highly efficient and reliable device of the character set forth. With this object in view, the invention resides in the novel subject matter hereinafter described and claimed, the description being supplemented by the accompanying drawing.

Figure 1 is a side elevation of a wrench constructed in accordance with my invention.

Fig. 2 is a side elevation partly in section, showing the different relation of parts.

Fig. 3 is a transverse sectional view as indicated by line 3—3 of Fig. 1.

35 In the drawings above briefly described, the numeral 1 designates a C-shaped body, one of whose curved ends 2 constitutes a fixed jaw for engagement with a pipe or the like. The other end of the body 1 is bifurcated as indicated at 3 and the front end of a handle 4 is pivoted between the furcations, by means of a rivet or the like 5. A longitudinally curved movable jaw 6 is provided with a bifurcated end 7 which straddles the intermediate portion of the body 1 and is pivoted thereto by a rivet or other suitable means 8. The jaw 6 is movable toward and

from the fixed jaw 2 and the front end of the handle 4 which extends slightly beyond the pivot 5, is cut on an oblique line to form 50 a cam 9 to slide longitudinally along the rear edge of the movable jaw 6, for the purpose of retaining it in tight contact with the work, when the handle is operated.

The front side of the door 6 is preferably 55 formed with a recess 10 receiving a removable slip or jaw block 11 having teeth 12 to engage the work, said slip or block being secured in the recess 10 by a removable pin 13. Whenever the teeth are so worn that they 60 do not properly grip the work, the pin 13 may be withdrawn, permitting replacement of the slip or jaw block 11.

By employing the construction disclosed, a tool of extreme simplicity is provided and 65 hence it may be cheaply and easily manufactured and marketed, yet a very efficient article is provided which cannot possibly slip upon the work, as the gripping action is increased with operation of the handle 4. 70

I claim:

A pipe tong comprising a C-shaped body having its ends curved inwardly toward each other, one of said ends constituting a fixed jaw, a handle pivoted near its front end to the other end of said body and having an obliquely cut front end disposed between the ends of said body, and a movable jaw pivoted at one end to the intermediate portion of said body, the other end of the jaw being interposed between said fixed jaw and the obliquely cut front end of said handle, said obliquely cut end having a single point contact with the free end portion of said movable jaw, said point of contact being disposed at a point comparatively remote from the pivot of the movable jaw and the distance between the point of contact and the pivot point of the movable jaw being the same at all times, whereby to obtain a comparatively powerful leverage. 90

In testimony whereof I have hereunto affixed my signature.

NEWTON FELLABAUM.
